WILLIAM WESLEY HICKS, OF SAN FRANCISCO, CALIFORNIA.

ELECTRICAL HEATING ELEMENT.

Application filed June 27, 1927. Serial No. 201,620.

This invention relates generally to electrical heating elements such as are incorporated in various electrical heating appliances.

5 Many forms of electrical heating appliances are constructed so that the resistance conductors are entirely concealed from view. For example in the case of electrical hot plates employed for cooking purposes, 10 it is customary to utilize an imperforate metal plate having insulated resistance conductors in close thermal contact with the lower face of the plate. When the controlling switch for such an appliance is turned 15 on, the operator has no positive way of determining immediately whether or not the resistance conductors are being energized, since considerable time is necessary for the entire plate to be perceptively heated. Furthermore unless complicated external signaling means is employed, an operator has no 20 means for visually determining whether or not a closed appliance of this type is being energized even though the plate has attained 25 a considerable temperature. In testing electrical heating appliances having heating elements of this kind, electricians waste considerable time in determining the presence of an open circuit due either to a burned out 30 resistance element or to an open fuse.

It is an object of this invention to incorporate means in a heating element of the closed type for positively indicating to the operator whether or not the resistance conductors are being energized.

15 It is a further object of this invention to incorporate means forming a minor portion of the heat transferring surface of a heating element, for providing a visual indication of the temperature condition of the heating conductor.

It is a further object of this invention to utilize fused quartz for the purpose of transmitting a light indication from a resistance conductor which is concealed within opaque heat conducting material.

Further objects of this invention will appear from the following description in which I have set forth the preferred embodiment of my invention. It is to be understood that the appended claims are to be accorded a range of equivalents consistent with the state of the prior art.

Referring to the drawing:

5 Figure 1 is a top plan view of a hot plate

incorporating the principles of this invention.

Fig. 2 is a cross sectional view taken along the line 2—2 of Fig. 1.

Fig. 3 is a bottom plan view of the hot 60 plate shown in Fig. 1, the bottom casing being removed to show the positioning of the resistance conductors within grooves provided on the lower face of the heat conducting members.

65 Fig. 4 is a cross sectional detail illustrating a modified form of signaling means for indicating the temperature condition of a resistance conductor.

Fig. 5 is a view similar to Fig. 4 showing a further modified form of signaling means.

The invention may be outlined briefly as comprising a heat conducting member of opaque material, such as ordinary cast iron, 75 the outer face of the member forming a heating transferring surface, and the inner face being in heat absorbing relationship with a resistance conductor. Extending through the heat conducting member there is a piece of light transmitting material 80 capable of withstanding a relatively high temperature, as for example a piece of fused quartz. The inner end of this piece of quartz is exposed to the light glow of the 85 resistance conductor while the outer end preferably terminates contiguous with the outer face where it may be viewed by the operator.

Referring now to the specific embodiment 90 of the invention illustrated in the drawing, there is shown an electrical hot plate comprising a relatively flat member 10 of opaque heat conducting material, such as cast iron or other suitable metal. In thermal contact with the lower face of the member 10, are the coiled resistance conductors 11 which for convenience may be divided into two resistance elements, one serving to heat the center portion of the plate and the other serving 95 to heat the outer portion. In order to secure efficient transfer of heat from the conductors 11 to the member 10, these conductors are preferably disposed between ribs 12 formed upon the lower face of member 10 and integral therewith. For example these ribs 100 may be so disposed upon the plate so as to form a spiral groove 13. When the member 10 is made of metal or electrical conductive material, the resistance conductors 11 are in-

sulated by suitable means such as refractory beads or tubes 14 which are sufficient in diameter to substantially fill the groove 13. The refractory tubes and the resistance conductors are retained in operative position between the ribs 12 as by means of unvitrified refractory cement 16. As is usual with hot plates of this kind, the member 10 is retained in operative position upon an electrical range 10 top 17 or other suitable support, and has its lower face enclosed by suitable means such as a metal pan 18. Terminal connectors 19 mounted upon this pan serve as a means for making electrical connections to the terminal wires of the resistance conductors 11.

In a hot plate such as described above it is impossible for an operator to actually see the resistance conductors in order to determine if they are at a glowing temperature. 20 In this invention however such a temperature condition is indicated to the operator by means of one or more members 21 of light transmitting material which extend thru the heat conducting member 10. The material of which these light transmitting members are constructed must be such that they will withstand the relatively high temperatures and sudden temperature changes to which the plate is normally subjected. For 25 example I may employ a special form of glass capable of withstanding a high temperature, but the material which I prefer to employ is transparent fused quartz. Not only will fused quartz withstand high temperatures and sudden temperature changes without breakage, but it has the peculiar property of transmitting light in the direction of its axis, even tho the axis may be bent at an acute angle. A number of different expedients may be employed for exposing the inner end of member 21 to the adjacent portion of one of the resistance conductors. In Figs. 2 and 3 I have shown that portion of the resistance conductor adjacent 30 to the inner end of member 21 as being insulated by means of a special tube 22 of light transmitting material such as fused quartz. For retaining the member 21 in position, it may be tapered upwardly and seated within a conical aperture 23 with the inner end of the member 21 in abutment with the periphery of the fused quartz tube 22.

As a modification of the structures shown in Figs. 2 and 3, I may construct the quartz tube 22 and the member 21 integral as shown in Fig. 4. Thus in this instance the quartz tube 122 which serves to insulate the resistance conductor from the walls of the metal heat conducting member 10, is provided with 45 an integral projecting member 121 which extends thru an aperture 26 in the heat conducting member 10.

A further modification is shown in Fig. 5 in which the light transmitting member 221 is formed to provide a lens for magnifying

a light indication. In this instance the refractory tube 27 covering that portion of the resistance conductor adjacent to the member 221 is provided with an aperture 28 for exposing the lower end of member 221 to the 70 light glow from the resistance conductor. The upper and lower ends of member 221 are provided with curved convex surfaces 29 and 31 so that a maximum amount of light glow will be transmitted to member 221 and dif- 75 fused from the upper end thereof.

As shown in Figs. 1 and 3, a plurality of light indicating means may be employed with one heating appliance and where the heating appliance employs two separate resistance elements, as with the appliance described above, I preferably utilize an indicating means for each element. Thus as shown in Figs. 1 and 3 one of the light transmitting members 21 is operatively positioned 80 with respect to the outer resistance conductor while the other is operatively positioned with respect to the inner conductor.

When one or more of the resistance conductors are being energized, the reddish 90 light glow transmitted from the radiant resistance conductor will be transmitted thru the fused quartz member and will at once be visible to an operator. In testing the plate for a burned out resistance element, 95 or to determine if a fuse is open, the electrician can at once see if one or both of the elements are being energized without waiting for the plate to become heated, or if one of the heating elements has become open 100 circuited, he can determine which element is still operable. As the upper end of the quartz members terminate contiguous with the upper face of the heat conducting member 10, or what may be termed the heat 105 transferring surface, normal operation of the device is not impaired and all of the advantages of a hot plate of the closed type are still retained.

I claim:

1. In an electrical heating appliance, a resistance conductor adapted to be heated to a glowing temperature, metallic means arranged to substantially conceal said conductor, said metallic means including an imperforate heat transferring surface of substantial area, and means for signalling the temperature condition of the conductor to an observer comprising a member of light transmitting material, one end of said member terminating adjacent a portion of said conductor, and the other end thereof extending thru said metallic means and forming a portion of said heat transferring surface.

2. In an electrical heating element, a resistance conductor adapted to be heated to a glowing temperature, metallic means adapted to substantially conceal said conductor, said metallic means including an imperforate heat transferring surface of

110

- substantial area, and means for signalling the temperature condition of the conductor to an observer comprising a member made of fused quartz, one portion of said member terminating adjacent a portion of said conductor, and another portion of the member extending thru said metallic means and forming a minor portion of the heat transferring surface.
- 10 3. An electrical hot plate of the closed type comprising a relatively flat member of heat conducting material, a resistance conductor in heat transmitting relationship with the lower face of said member, the upper face of said member forming a heat transferring surface of substantial area, and a plug of fused quartz positioned in said member, the inner portion of said plug being exposed to a portion of the conductor, 20 and the outer portion of said plug having a surface contiguous with said heat transferring surface.
4. An electrical hot plate of the closed top type comprising a relatively flat opaque member of heat conducting material, a resistance conductor in heat transmitting relationship with the lower face of said member, the upper face of said member forming a substantially planar heat transferring surface of substantial area for applying heat 25 to the bottom of a cooking utensil, and a plug of light transmitting material inserted in said member, the inner portion of said plug having a surface continuing the continuity 30 of said heat transferring surface.
4. An electrical hot plate of the closed top type comprising a relatively flat opaque member of heat conducting material, a resistance conductor in heat transmitting relationship with the lower face of said member, the upper face of said member forming a substantially planar heat transferring surface of substantial area for applying heat 35 to the bottom of a cooking utensil, and a plug of light transmitting material inserted in said member, the inner portion of said plug having a surface continuing the continuity of said heat transferring surface.

In testimony whereof, I have hereunto set my hand.

WILLIAM WESLEY HICKS.
